TOP ROLL PRESSURE MECHANISM

Christopher Walsh, Pawtucket, R. I., assignor to
 H & B American Machine Company, a corpora-
 tion of Maine

Application May 1, 1939, Serial No. 270,969

11 Claims. (Cl. 19—136)

This invention relates to textile drafting machines, such as speeders, spinning and analogous machines, and more particularly to an improvement in the fulcrum and its support for sustaining the usual weighted lever of the stirrup for the pressure system for the top roll saddles; and has for one of its objects the adjustment of the fulcrum into different adjusted positions to compensate for the changes in the settings of the

10 draft rolls and/or the adjustment of the stirrup.

Another object of the invention is the provision of an adjustable support for the fulcrum of the weight lever in which both the support and the fulcrum of the lever may be readily shifted bodily as a unit relative to the usual roller beam so as to maintain the required position of the fulcrum for all adjustments of the stirrup and/or changes in the roll settings.

Another object of the invention is to provide 20 manually adjustable means for sustaining the fulcrum of the weight lever and capable of being readily moved and set into the adjusted position required without the use of tools and without loosening and tightening of a clamping bolt.

25 Another object of the invention is to provide a support means for the fulcrum of the weight lever capable of being readily moved into adjusted positions by a manual pulling or pulling movement to change its position relative to the roller beam.

30 Another object of the invention is to provide a slidable fulcrum support for sustaining the weight lever adapted to be readily pushed or pulled into various required adjusted positions and capable of being self-locking therein upon removal of the 35 applied manual force for effecting its movement to such position.

Another object of the invention is to provide a 40 slidable support of the above character for the fulcrum of the weight lever capable of being readily lengthened or shortened relative to the roller stand for varying the position of the fulcrum to compensate for all adjustments of the stirrup and/or changes in the roll settings so as to maintain the required relation between the 45 fulcrum and such parts in which the locking of the fulcrum support in its various adjusted positions or its release therefrom for sliding movement may be had by a tilting operation.

With these and other objects in view, the invention 50 consists of certain novel features of construction, as will be more fully described, and particularly pointed out in the appended claims.

In the accompanying drawings:

Fig. 1 is a transverse sectional view of a part 55 of a speeder or analogous machine provided with

my improved adjustable slide bracket for the fulcrum of the weight lever, and showing the usual drawing rolls positioned in their wide settings;

Fig. 2 is a transverse sectional view of the general machine shown in Fig. 1 but showing the front saddle member represented in Fig. 1 located in a different adjusted position and carrying a shorter rear saddle member in reversed position to that of the rear saddle shown in Fig. 1 with the weight and the fulcrum at different positions on the weight lever, and also showing the drawing rolls as moved into a closer setting with the slide bracket and the fulcrum for the weight lever moved into a proper position for compensating for the adjustment in the roll settings;

Fig. 3 is a perspective view of the locking block for detachably securing the adjustable slide bracket in its various adjusted positions; and

Fig. 4 is a perspective view of the slideable 20 bracket which carries the fulcrum element for sustaining the weight lever.

In certain classes of textile machines, such as speeders, spinning and similar machines, it is the usual practice to provide a weighting device for applying the required pressure on the top rolls; one usual form of device for this purpose comprises a top roll saddle, a stirrup having its upper end engaging the saddle, and a weight carrying lever for applying the required pull on the stirrup. The common practice has been to rockably mount the weighted lever on a fulcrum eye which is threaded into a hole in the roller beam of the machine. This method of fulcruming the weight lever, however, has proven objectionable owing to the necessity of making adjustments in the roll settings and of relocating the fulcrum and the stirrup positions so as to compensate for the various adjusted position of the roll spacing but, owing to the fixed and definite position of the fulcrum in the previous weighting systems, no provision was made for such adjustment of the fulcrum, and in order to overcome these prior difficulties above noted and to obtain the above mentioned advantageous results, I have provided a simple and improved fulcruming arrangement for sustaining the weight lever, in which I mount the fulcrum element on a slideable bracket which is rockably arranged on a fixed support, preferably the usual roller beam, and this slide is so mounted thereon as to be manually adjustable into various rearwardly extended adjusted positions for providing a compensating adjustment in the position of the fulcrum element when the settings of the draft

rolls are changed; and I also provide retaining means for holding the slide locked in its adjusted locations which comprises a locking block having a portion extending over the top surface 5 of the slide racket in which the opposed surfaces of the locking block and the fulcrum support bracket respectively are provided with means having interlocking engagement with each other and consisting of serrations of saw-teeth adapted to 10 coact with each other upon tilting movement of the fulcrum support bracket in one direction to retain the same in adjusted position, and in which release of the bracket for sliding movement into a different position whereby adjustment 15 of the bracket to and fro laterally of the roller beam may be readily obtained without the use of tools and simply by a manual tilting movement of the bracket in another direction to release the bracket from its locked position for 20 free sliding movement; and the following is a more detailed description of the present embodiment of this invention, illustrating the preferred means by which these advantageous results may be accomplished.

25 In the drawings; 10 generally designates the usual roller beam of a speeder or a spinning frame, having suitably mounted on its top surface a plurality of roller stands 12, in the present instance a portion of one being shown, on which are 30 mounted the lower drawing rolls 13, 13a and 13b, which are suitably journaled for rotation in the usual adjustable bearing blocks 14, 14a and 14b on the roller stand for changing at will the relative spacings between the bottom rolls, as is well 35 known construction in the art. Disposed above the bottom rolls 13 are the usual top rolls 15, 15a and 15b, which are rotatably mounted on adjustable cap bar nibs 16 suitably carried on the usual cap bar 18. The pressure on the top 40 rolls is applied by the usual compound pressure saddle consisting of a front saddle 19, which is fitted by means of a concave bearing to the neck of the forwardly disposed top roll 15, and a back saddle 20 which is adjustably mounted on the 45 front saddle 19 and when adjusted and set relative thereto transmits the pressure only to the intermediate top roll 15a and the back top roll 15b. An adjusting bolt 21 rotatably carried by a protuberance 22 on the front saddle 19 has 50 threading engagement within a suitable threaded sleeve portion 23 at the top end of the usual stirrup member 24 for adjustment of the same relative to the saddle so as to change the position of engagement of the knife edge 25 depending 55 from the underside of the stirrup sleeve 23, by means of which pressure is applied to the front top roll saddle. The lower end of the stirrup 24 is pivotally connected to the usual weight lever 26 by means of a pivot pin 27.

60 When the pairs of drawing rolls 13, 15; 13a, 15a and 13b, 15b are adjusted to provide closer roll settings, as depicted in Fig. 2, then the usual rear saddle member 20 is replaced by a shorter rear saddle member 20' which is hung 65 from the front saddle 19 in a reversed position with its roll-straddling means engageable with the back top roll 15b.

As illustrated, the weight lever 26 is provided at one end with a hook-shaped formation consisting of a short arm 28 having a pair of deep notches 29 adjacent each other in the top surface of the arm 28 for selective engagement and insertion through an eye 30 forming the fulcrum element for the weight lever 26. A weight 31 suspended from the free end of the weight lever

26 by means of a link hook 32 acts to apply the required pull on the stirrup. The link 32 is suspended from one of several deep notches 33 adjacent the free end of the longer lever arm of the weight lever 26 to transmit thereto the desired weighting pressure which in turn is transmitted through the stirrup to the top roll saddles 19 and 20 respectively.

27 The fulcrum eye 30 is mounted in an upright position for sustaining the weight lever for rocking movement and comprises a lower threaded stud portion 34 which is adjustably secured in place within an internally threaded boss 35 upstanding from the top surface of a slide bracket generally designated 36, which is adjustably mounted on the roller beam 10 of the textile machine for sliding movement laterally of the roller beam and the draft rolls into different adjusted positions for positioning the fulcrum eye 30 in a position to compensate for adjustments in the roll settings. A locking block 37 rigidly secured to the roller beam of the machine by means of a clamping bolt 38 has detachable engagement with the slide bracket 36, as will be hereinafter described, for retaining the bracket 28 in adjusted positions.

28 Referring to Fig. 4, the slide bracket 36 is shown in detail and consists of a U-shaped body having a pair of elongated parallel arms 39, the top surfaces of which over a substantial portion 30 thereof are transversely corrugated or serrated to provide a series of saw teeth 40 which are selectively engageable upon longitudinal shifting movement of the slide 36 with another set of similarly shaped corrugations of saw-teeth 41 35 formed on the bottom surface of each of the arms 42 of the bifurcated locking block 37.

29 As shown in Fig. 3, the locking block 37 is of generally T-shaped form having a narrow shank portion 43 which is normally received in the elongated space between the opposed arms 39 of the slide and serves to guide the slide during its adjustment laterally of the roller beam upon release of the teeth on the slide from interlocking engagement with the teeth carried by the arms 42 of the locking block. The arms 42 of the locking block are integral with its shank portion and they normally extend longitudinally over the top of the arms 39 of the slide bracket in the assembled position of the parts. The height of 40 the shank 43 is made sufficient to provide a slight clearance between the top of the slide and the arms to permit rocking or tilting movement of the slide 36 upwardly and downwardly about the shank for effecting a locking engagement of the 45 slide with the block when the slide is raised and its release upon being depressed to disengage the teeth and free the slide for longitudinal shifting movement into its desired adjusted positions.

30 The operation of the device will be apparent 60 from the foregoing disclosure: When it is desired to adjust the fulcrum element so as to position the same in its correct position relative to the stirrups and the rolls after adjustment of roll settings from their wide setting to various degrees 65 of closeness, or vice versa, the rearwardly extending portion of the slide bracket 36 overhanging the roller beam is first depressed manually to tilt it downwardly for disengaging the teeth 40 from the teeth 41 of the locking block. The 70 slide bracket 36, thus freed from the block, is then shifted forwardly or rearwardly as desired by a pulling or a pushing movement. Thus the slide is pulled forward toward the roller beam to compensate for close settings of the rolls while 75

rearward shifting movement of the slide serves to position the fulcrum for compensating for the wider spacings of the rolls. To retain the slide in its adjusted position with the fulcrum in its required position, the manual pressure exerted on the slide 36 to shift the same is withdrawn, whereupon the action of the weight 31 will lift up the extended end of the slide bracket carrying the fulcrum to cause interlocking engagement of the serrations or saw teeth 40 and 41 and firmly secure and retain the slide in its adjusted position.

By means of my simple adjusting arrangement it is therefore possible for the operator to make the necessary adjustments of the fulcrum and the weight lever to obtain the proper position of these parts without the use of tools or of the necessity for bolts. By utilizing a construction of this type I am able to bodily shift the weight lever, the stirrup and the fulcrum to various positions for compensating for the adjustments in the roll spacings without changing the leverage of the weighting system or the weighting pressure employed and applied to the top rolls. Furthermore, by means of this construction I am also able to maintain the line of pressure action of the stirrup in a plane substantially parallel to the respective vertical planes containing the longitudinal axes of each pair of upper and lower draft rolls in all adjusted positions of the fulcrum and its slide support. In other words, the line of action of the stirrup will be maintained at substantially right angles to the general plane of the saddles for all positions of adjustment of the stirrup and the fulcrum of the weight lever.

The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. In a top roll pressure apparatus in a textile or analogous machine, the combination with a stirrup connected at one end to a weight lever and a front pressure saddle connected to the other end of the stirrup resting on the front top roll, of a fulcrum element on which the weight lever is hinged for pivotal movement, a fixed support, a tiltable slide on said support supporting said fulcrum element, said slide being manually shiftable transversely relative to said support into different adjusted positions thereon when tilted in one direction and slid on the support, and means for detachably securing said slide in its various adjusted positions, said means being provided with a tooth to engage a similar formation upon the slide to hold the same fixed when the latter is released and tilted in a different direction from that for normally effecting the release and manual shifting movement of the slide with respect to the support.

2. In a top roll pressure apparatus in a textile or analogous machine, the combination with a stirrup connected at one end to a weight lever and a front pressure saddle connected to the other end of the stirrup resting on the front top roll, of a fulcrum element on which the weight lever is hinged for pivotal movement, a fixed support, a tiltable slide on said support supporting said fulcrum element, said slide being manually shiftable in a generally horizontal direction relative to said support into different

adjusted positions thereon when tilted in one direction and slid on the support, and a locking member for detachably securing said slide in its various adjusted positions said locking member being provided with a serrated portion having interlocking engagement with cooperating serrations on the slide to hold the same fixed when the latter is released and tilted in a different direction from that for normally effecting the release and manual shifting movement of the slide with respect to the support.

3. In combination in a textile drafting machine, relatively adjustable pairs of top and bottom draft rolls, a top roll pressure device for applying pressure to a plurality of top rolls comprising a front saddle member resting on two of the top rolls a front saddle member having fulcruming engagement with said rear saddle member and resting on the front top roll, a stirrup hung from said front saddle and extending generally downwardly therefrom between adjacent pairs of draft rolls, a weight lever pivoted to the lower end of said stirrup and having an arm portion for rocking on a fulcrum element, a roller beam, a fulcrum element pivotally engaging said arm portion of the weight lever and positioned below said draft rolls for supporting the weight lever, a rockable slide carrying said fulcrum element and adapted to be adjusted by being rocked downwardly and shifted laterally of said roller beam so as to be slid in an extended position relative thereto for positioning the fulcrum member into different positions of adjustment and locate the fulcrum in its correct position relative to the setting of the draft rolls and at substantially right angles to the line of action of the stirrup without changing the pressure on the top rolls, and a locking member fixedly secured to said roller beam and having a serrated portion engageable with a serrated portion on said slide upon rocking movement of the slide in an upwardly direction when the manually applied force for actuating the slide is withdrawn.

4. In a top roll saddle mechanism, the combination with a weighted lever for a top roll saddle, of a support, a slide on said support movable transversely of the support into different selected adjusted positions, a fulcruming member for sustaining said lever carried by and movable with said slide, and means associated with the support detachably securing the slide in all adjusted positions, said securing means and said slide being provided with cooperating portions having interengaging formations, said slide being capable of rocking movement in one direction to effect disengagement of said formations for permitting the adjustment of the slide transversely of the support, and when positioned in an adjusted position being rockable in another direction to effect interengagement of said formations for maintaining the slide in such adjusted position when said lever is sustained by the fulcruming member.

5. In a top roll saddle mechanism, the combination with a weighted lever for a top roll saddle, of a support, a slide on said support movable transversely of the support into different selected adjusted positions, a fulcruming member for sustaining said lever carried by and movable with said slide and a member fixedly secured to said support against movement relative to the same and positioned thereon for detachably securing and retaining the slide in all adjusted positions, said last-named member and

said slide being provided with cooperating portions having inter-engaging formations, said slide being rockable in one direction to effect disengagement of said formations, and being rockable in the opposite direction to effect inter-engagement of the said formations when said lever is sustained by the fulcruming member.

6. In a top roll saddle mechanism, the combination with a weighted lever for a top roll saddle, of a support, a slide on said support movable transversely of the support into different selected adjusted positions, a fulcruming member for sustaining said lever carried by and movable with said slide, and means associated with the support detachably securing the slide in all adjusted positions, said securing means and said slide being provided with cooperating portions having interengaging formations, said formations being separable upon relative movement of the parts on which they are located when moved in a direction substantially at right angles to the direction of the transverse adjustment of the slide relative to the support.

7. In a top roll saddle mechanism, the combination with a weighted lever for a top roll saddle, of a fixed support, an upstanding fulcruming member for said lever, a shiftable member on which said fulcruming member is supported and movable with the shifting movement of the support, said shiftable member being movable transversely of said fixed support, the arrangement of said shiftable support member being such that it is capable of rocking movement in an up and down direction relative to said fixed support to effect either the connection or the release of said shiftable member with respect to the fixed support, said shiftable member when disconnected from said fixed support being manually shiftable transversely of the fixed support into different rearwardly-extended positions relative thereto for positioning the fulcruming member in different horizontally adjusted positions, and means associated with said fixed support for retaining and detachably securing the shiftable fulcrum-carrying member in all adjusted positions, said retaining means and said shiftable member having cooperating interengaging toothed formations.

8. In a top roll saddle mechanism, the combination with a front top roll, of a front saddle member resting on the front top roll, a stirrup hung from said front saddle and adjustably fulcrumed thereon for applying weight thereto, a weighted lever supported by said stirrup, a fulcruming member for sustaining said lever, a support, a rockable slide on said support adjustable transversely of the support into different selected adjusted positions, and means for detachably securing and retaining said slide in all adjusted positions, said means being provided

with cooperating portions having interengaging toothed formations for maintaining the slide in its adjusted position when said lever is sustained by the fulcruming member, said formations being maintained in interengaging relationship by the normal effect of the weighted lever.

9. In a top roll saddle mechanism, the combination with a weighted lever for a top roll saddle, of a support, a slide on said support movable transversely of the support into different selected adjusted positions, a fulcruming member for sustaining said lever carried by and movable with said slide, and a member on said support having a part positioned above and overlying the slide for detachably securing and retaining the slide in all adjusted positions, said overlying part of the last-named member and said slide being provided with cooperating portions having interengaging formations, said slide being rockable downwardly to effect disengagement of said formations, and being rockable upwardly to effect interengagement of the said formations when said lever is sustained by the fulcruming member, said formations being maintained in interengaging relationship by the normal effect of the weighted lever.

10. In a top roll saddle mechanism, the combination with a weighted lever for a top roll saddle, of a support, a bifurcated slide on said support movable transversely of the support into different selected adjusted positions, a fulcruming member for sustaining said lever carried by and movable with said slide, said slide being rockable on the support toward and from the same, and a retaining member for said slide fixed on the support and embraced on opposite sides by the bifurcated parts of said slide and being provided with spaced arms extending over the tops of such bifurcated parts of the slide, said arms and said bifurcated parts of the slide being provided with cooperating portions having interengaging toothed formations, said slide being rockable downwardly to effect disengagement of said formations for permitting adjustment of the slide transversely of the support, and being rockable in an upwardly direction to effect interengagement of said formations when the slide is positioned in an adjusted position and with the weighted lever in a sustained position by the fulcruming member, said formations being maintained in interengaging relationship by the normal effect of the weighted lever.

11. A slide for use in a top roll saddle weighting mechanism for sustaining the usual weighted lever comprising a bifurcated member, said member having a slot and two parallel arms each of which is provided with a portion having a toothed formation, and means for threadingly mounting a fulcruming member for the weighted lever.

CHRISTOPHER WALSH. 60
